UNITED STATES PATENT OFFICE.

CHARLES SUMNER SIMMERS, OF COLD SPRING, NEW YORK.

JARRING-MACHINE.

991,381.

Specification of Letters Patent.

Patented May 2, 1911.

Application filed April 27, 1910. Serial No. 557,893.

To all whom it may concern:

Be it known that I, CHARLES S. SIMMERS, a citizen of the United States, and a resident of Cold Spring, in the county of Putnam and State of New York, have invented a new and Improved Jarring-Machine, of which the following is a full, clear, and exact description.

This invention relates to a new and improved jarring machine of a type adapted to settle, shake down or even agitate material.

An object of this invention is to provide a device which will be simple in construction, inexpensive to manufacture, strong, durable, readily accessible for the purpose of repairing and renewing of the parts, and both reliable and simple in its operation.

A further object of this invention is to provide a device in which the amount or extent of the jar can be varied according to the character of the work which it is desired that the machine shall accomplish.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a side view in elevation; Fig. 2 is a vertical section on the line 2—2 of Fig. 1; and Fig. 3 is a horizontal section on the line 3—3 of Fig. 2.

Referring more particularly to the parts of the device, 1 indicates a base or frame, which may be of any suitable light, strong structure, and is preferably provided with upwardly-extending members 2 and 3, which are adapted to support legs 4 and 5, which in turn support a table 6, on which the material to be treated is placed either directly or in a suitable receptacle.

Rotatably supported on the frame 1 in any suitable manner, there is provided suitable driving means in the form of a shaft 7, which has at its outer end a pulley 8 intended to indicate a suitable source of motive power. The shaft 7 also is provided with a gear 9, which meshes with gears 10 and 11 on each side thereof, secured to shafts 12 and 13, which in turn are rotatably supported in any well known manner by the frame 1. Each of these shafts 12 and

13 is provided with a pair of cams 14 and 15 extending in opposite directions and slidably secured to the shafts 12 and 13 in any well known manner, as by means of keys 16. 60 These cams 14 and 15 are of the gravity drop type, and a peculiar thing to be noted about them is that they are conical in form, so that the amount of drop varies from a minimum at their inner end to a maximum 65 at their outer end. The table 6 is provided with a plurality of cam followers 17 and 18 in the nature of conical rollers rotatably supported on brackets 19 and 20 secured to the table 6. 70

It will be seen that by the rotation of the shafts 12 and 13, the table 6 will be given a jarring and jolting motion, which is very efficient in settling certain classes of material and in stirring up other classes of material. The cams, if desired, may be set so that they will permit all the followers to drop at the same instant and give an even jar over the whole table, or, if desired, they may be set so as to permit the followers to drop in pairs in an alternate manner, so as to give a rocking jar to the table, as is sometimes desired in the case of manufacturing chocolate. For the purpose of varying the amount of the jar, the cams are provided with collars 21 and 22, which are secured to the cams in such a manner as to permit the rotation thereof, and yet so as to permit a positive connection whereby the cams may be shifted longitudinally on the shaft by the collars. These collars 21 and 22 are provided at their lower ends with pins 23, which engage in slots 24 on the ends of levers 25 and 26. These levers are pivotally connected at approximately their middle by any suitable means, such as a bolt 27. Adjacent one of the ends of each of these levers, there are provided therein slots 28, which are engaged by bolts 29 secured to oppositely threaded nuts 30 and 31, 100 which engage oppositely-threaded screws 32 and 33 on a shaft 34. The shaft 34 is rotatably supported in the base 1 in any well known manner, and is provided at one end with a suitable operating device in the nature of a hand-wheel 35, whereby the rotation of the shaft 34 will spread apart or draw together the levers 25 and 26, according to the direction of rotation, and thus spread apart or draw together the cams 14 110 and 15. The nearer these cams approach the center of the frame 1, that is to say, the

farther inward they travel, the greater will be the drop of the cam followers 17 and 18 because of the increased dimensions of their conical eccentricity.

5. For the purpose of guiding the table 6 and movably retaining it on the frame, there are provided a plurality of guides 44, which engage ways 45 on the legs 4 and 5 of the frame, the latter being in the form 10 of angle-irons secured in any well known manner to the legs.

If desired, shock-absorbing cushions can be placed between the contacting surfaces of the table 6 and the legs 4 and 5, so as to 15 deaden the sound due to the impact.

The operation of the device will be readily understood when taken in connection with the above description. The material is placed on the table 6, either directly or in 20 a suitable receptacle, and the device started by rotating the shaft 7, which in turn rotates the shafts 12 and 13. If the cams are all set in unison, the table will be given a direct vertical up-and-down jarring motion, 25 which will treat the material in the manner desired. If desired, the cams can be set in any other relation, for example, alternately in pairs, so as to give a rocking, jarring motion to the table. The extent of the jar- 30 ring can be increased by bringing the cams closer together, and can also be decreased by separating the cams.

While I have shown one embodiment of my invention, I do not wish to be limited to 35 the specific details thereof, but desire to be protected in various changes, modifications and alterations which I may make within the scope of the appended claims.

Having thus described my invention, I 40 claim as new and desire to secure by Letters Patent:

1. The combination with a frame, of a table movably connected to said frame, and a plurality of jarrers for jarring said table 45 in a vertical direction, said jarrers being adjustable to vary the drop of the table.

2. The combination with a frame, of a vertically movable table connected to said frame, a cam for moving said table vertically, said cam having a drop therein of gradually increasing dimensions, and an adjuster for rendering different portions of 50 said cam active.

3. The combination with a frame, of a 55 vertically-movable table connected to said frame, a cam having a varying eccentricity

to produce varying drops, a follower coöperating with said cam to move said table vertically, and means for varying the relative positions of said cam and said follower, 60 whereby the movement of said table is varied.

4. The combination with a frame, of a shaft rotatably supported in said frame, a pair of cams of varying eccentricity mounted on said shaft, a vertically-movable table on said frame, followers on said table engaging said cams, and means for adjusting the relative positions of said followers and said cams for the purpose of varying the drop of 70 said table.

5. The combination with a frame, of a shaft rotatably mounted on said frame, a pair of cams having varying eccentricity slidingly mounted on said shaft, a table movably connected to said frame, means for operatively connecting said table to said cams, levers connected to said cams, and means for simultaneously moving said levers whereby 75 said cams are simultaneously adjusted relative to each other.

6. The combination with a frame, of a pair of shafts rotatably mounted on said frame, a pair of conical cams having eccentric drops of varying depths, slidingly 80 mounted on each of said shafts, and mechanism for adjusting the position of said cams, whereby different portions thereof are rendered active for the purpose of moving said table.

7. The combination with a frame, of a pair of shafts rotatably mounted on said frame, a pair of conical cams having eccentric drops of varying depths, slidingly 85 mounted on each of said shafts, and mechanism for adjusting the position of said cams, whereby different portions thereof are rendered active for the purpose of moving said table, said mechanism comprising a pair of levers pivotally connected together and 90 operatively connected to said cams, a nut on each of said levers, a shaft having oppositely threaded portions thereon engaging said nuts, and means for operating said shaft.

In testimony whereof I have signed my 105 name to this specification in the presence of two subscribing witnesses.

CHARLES SUMNER SIMMERS.
